UNITED STATES PATENT OFFICE.

GEORG GRABE, OF NIKOLASSEE, NEAR BERLIN, GERMANY, ASSIGNOR TO SIEMENS & HALSKE A. G., OF BERLIN, GERMANY.

AUTOMATIC TELEPHONE-EXCHANGE SYSTEM.

1,109,216.

Specification of Letters Patent.

Patented Sept. 1, 1914.

Application filed December 11, 1909. Serial No. 532,711.

To all whom it may concern:

Be it known that I, GEORG GRABE, subject of the German Emperor, residing at Nikolassee, near Berlin, Germany, have invented 5 certain new and useful Improvements in Automatic Telephone-Exchange Systems, of which the following is a specification.

My invention relates to an automatic telephone-exchange system, in which the subscribers are connected by way of "first" and 10 "second", and so on, selectors and connectors which are located in a central station or exchange office and are set by means of impulses of current sent over the branches 15 of the line leading from the subscriber's station to the office by operating a numbered dial at the subscriber's station.

My invention relates particularly to that 20 type of automatic telephone-exchange systems, in which only a limited number of selectors and connectors are provided in the exchange office, the subscribers are divided into groups, and a calling subscriber's line 25 is connected with an idle so-called "first selector" by means of "call-seekers" which are started, when a call is present in the group of subscribers to which the switching device in question belongs, move step by step 30 and test the contacts of the lines of their groups of subscribers, and are stopped at the contacts of the calling line. The call-seeker must seek a calling line in this manner during the time which elapses between 35 the approach of the subscriber to his station and lifting the receiver until the first selecting impulse of current is emitted, since otherwise wrong connections would occur. As this interval is only short, however, after 40 moving only a limited number of steps the call-seeker must be able to reach the calling line, and my invention comprehends a "call-seeker system" which enables this in the case of a large number of groups of sub- 45 scribers.

The construction, connection and mode 50 of operation of the selectors and connectors is secondary for the essence of my invention, as my invention is equally suitable for all systems.

A primary object of my invention is to provide an arrangement by which the idle call-seekers of a group of subscribers, which 55 call-seekers execute, when being set, two kinds of switching steps or movements, *e. g.* lifting and turning or large and small steps,

are automatically set ready for receiving a call by preparatory steps of the former kind to sub-groups of the line contacts, and in which arrangement, when a call is present in a sub-group, the contacts of the calling line are reached by the call-seeker set to the sub-group in question by means of a less number of steps of the second kind, while another idle call-seeker is automatically set to this sub-group for receiving further calls 60 in this.

A further object of my invention is to provide a system in which, when only one call is present in a sub-group, only one call-seeker is moved along the contacts of the 65 same, whereas when two or more calls are present simultaneously in the same sub-group, two or more call-seekers are started in succession for receiving the calls and are moved simultaneously along the contacts of 70 this sub-group.

Another object of my invention is to cause 75 that at each sub-group only one call-seeker be set ready for receiving a call, whereas the remaining idle call-seekers of the group are in an initial position in the reserve condition and operate in succession when a call-seeker set to a sub-group is occupied receiving a call, the call-seeker which becomes idle 80 after the termination of a telephonic connection being returned into its initial position and joining the reserve seekers, and so many call-seekers being provided for each group of subscribers that even during the heaviest load each sub-group has ready another call-seeker for receiving calls.

Another object of my invention is to provide 85 a constructional form in which each call-seeker simultaneously tests two or more rows of line contacts, but only makes a connection with those contacts which appertain to the calling line.

When carrying my invention into practice, besides the call-seekers I preferably provide additional automatic switches which, when a call-seeker starts moving along the contacts of the subscribers' lines, start simultaneously with the call-seeker and are moved until the latter is connected with an idle "first selector", independently as to 90 whether the call-seeker is still in motion or whether it has already found the calling line.

My invention will now be described more particularly with reference to the accompanying drawings.

In said drawings:—Figure 1 shows the connection for connecting the subscribers' stations with the calling devices of the exchange station, Fig. 1^a is a detail view of the relay TR in larger scale. Fig. 2 the connection of the call-seekers of a group of subscribers' lines for seeking a calling line, Fig. 3 the connection of a "first selector", Fig. 4 the connection of a connector, and Figs. 5, 6 and 7 show modifications of connections for connecting the call-seekers with the "first selectors" by way of automatic intermittent switches, to wit Figs. 5 and 6 show the connection of the "first selector" common to a number of subscribers' groups by way of "second" call-seekers appertaining to these with the call-seekers of the group of subscribers, whereas Fig. 7 shows the connection of the call-seekers by way of "preliminary selectors" appertaining to these with a plurality of "first selectors" common to subscribers' groups. The parts of Figs. 2 and 3 in dotted lines show the supplementary means necessitated hereby at the call-seekers of the subscribers' groups, and at the "first selectors", respectively. The exchange office or central station is supposed to have a capacity for 1000 subscribers, so that the representation of "second selectors" is not necessary.

In the drawings, like reference characters designate like parts.

Reference characters comprising letters have indices which are omitted in the specification when one definite apparatus or part provided with like letters is not to be denoted.

Referring to the drawings, in Fig. 2 four call-seekers AS¹, AS², AS³, AS⁴ of one group of subscribers containing the subscribers' lines 300-399 are represented. The call-seekers are provided with test switch-levers o¹, o⁴ and line switch-levers o², o³, o⁵, o⁶ which are attached to the switch shaft of the call-seeker and, e. g. can be passed by means of two motions at right angles to one another, such as lifting and turning, over the test and line contacts of a group of 100 subscribers, sliding simultaneously over two rows of test contacts and two rows of line contacts. The ten horizontal rows of line and test contacts are divided into five sub-groups, so that each two rows form a sub-group. In connection with the call-seekers are switches SS whose switch springs or levers s¹, s², s³ are moved in the one direction simultaneously with the movement of the switch-levers o, whereas they remain stationary when the switch-levers o move in the other direction. By means of the switches SS¹, SS² . . . the sub-groups are tested automatically and continuously and call-seekers for accepting or receiving the calls in these are placed ready. One idle call-seeker is set by means of prepara-

tory steps on each sub-group, whereas the remaining idle call-seekers of the group remain in the initial position in the reserve condition. The switch spring s² of a call-seeker serves for engaging that sub-group to which the call-seeker is set; it slides over fixed contacts k¹⁰, k¹¹, k¹², k¹³, k¹⁴, k¹⁵, which are connected in order with the test line 10 of the initial position or the test lines 11, 12, 13, 14, 15 of the sub-groups. The switch spring s¹ serves for testing the sub-groups and slides over the contacts k¹, k², k³, k⁴, k⁵, which are connected in the corresponding order with the test lines 12, 13, 14, 15 of the sub-groups, and the ground line 16, and by way of the initial contact k⁰, which is connected by way of contact h¹ of the switch shaft of the call-seeker with the test line 10, when the seeker in question has moved out of its initial position. Contact k⁰ at switch SS¹ of the first call-seeker AS¹ is connected, in addition, with the test line 11 of the first sub-group formed here by the two top rows of contacts and in this manner is connected through to contact k⁰ of that call-seeker which is located in the initial condition as the first in the row in the group of subscribers in question. Switch spring s³ serves for receiving a call in the sub-group and slides over contacts k²¹, k²², k²³, k²⁴, k²⁵, connected respectively in the order stated with the lines 21, 22, 23, 24, 25 leading to the call devices of the sub-groups. Of these lines only line 24 connected with contact k²⁴ and line 25 connected with contact k²⁵ are represented in the drawings. The switch spring s¹ of each call-seeker is connected with a high resistance relay A which connects in circuit the lifting electromagnet H of the seeker when the sub-group, on which the switch spring s¹ tests, becomes free and relay A is not energized. Switch spring s³ of each call-seeker is connected with a relay B which connects in-circuit the turning electromagnet D for the switch shaft of the seeker as soon as its circuit by way of the calling line of the sub-group in question is closed.

The switch spring s² of each call-seeker keeps the test line of the sub-group in question "engaged" as long as there is no call in this sub-group and the rest contact b¹ of the relay B of this call-seeker is closed. As shown in Fig. 2, the call-seeker AS¹ is moved up to the top, i. e. fifth, sub-group, its spring s¹ resting on the grounded contact k⁵. The high resistance electro-magnet A¹ connected by the conductor 26 with the common battery feeder 100 is continuously energized by way of conductor 27, spring s¹, contact k⁵ and the grounded line 16 and prevents the interpolation of lifting electromagnet H¹ and consequently the switch shaft of the call-seeker being lifted farther. The switch spring s² grounded by way of

conductor 30 and contact b^1 of relay B¹ keeps the test wire 15 of the top sub-group "engaged" so that no additional seeker can be set thereon. Relay A³ of the call-seeker 5 AS³ moved up to the fourth sub-group is then traversed by a current which flows from the non-grounded pole of the common battery G (Fig. 1) by way of the main battery feeder 100 (Fig. 2), conductor 28, coil of relay A³, conductor 29, spring s¹, contacts k^4-k^{15} of the switch SS³, test line 15, to contact k^{15} and spring s² of switch SS¹, conductor 30, contact b^1 to ground and to the grounded pole of battery G. The continuously energized relay A³ keeps the circuit of the lifting electromagnet H³ of the call-seeker AS³ at the opened back rest contact and prevents this seeker moving forward to the fifth sub-group. In like manner switch 10 spring s² of switch SS³ keeps the test line 14 grounded by way of conductor 31 and contact b^1 of relay B³ and prevents a second call-seeker moving forward to the fourth sub-group. In similar manner each idle 15 call-seeker keeps "engaged" the third, second and first sub-groups. All the remaining idle call-seekers of the group are in the initial position. In the drawing the call-seekers AS² and AS⁴ occupy this position. The seeker (not shown) set to the first sub-group keeps the test line 11 grounded with its 20 switch spring s². By way of this grounded connection and the connection 9 at switch SS¹, conductor 8, contact h^1 , conductor 7 of the call-seeker AS¹, test line 10, contact h^0 and spring s¹ of switch SS², conductor 32, relay A² of the first call-seeker AS² in the 25 row of reserve seekers, conductors 33 and 100 there flows from battery G a current 30 which keeps relay A² energized and prevents this call-seeker moving forward. Also, the grounded spring s² of call-seeker AS² keeps relay A⁴ of the next reserve seeker AS⁴ energized by way of contact h^{10} 35 of switch SS², conductors 10, 6, contact h^3 of seeker AS³, conductor 5, contact h^0 and spring s¹ of switch SS⁴, conductor 34, coil of relay A⁴, conductors 35 and 100, and so on. Now when a call is present in a sub-group and relay B of the call-seeker set to 40 this sub-group is energized, as described hereinafter, by interrupting contact b^1 the grounding of the switch spring s² in question is done away with, and relay A testing 45 on this sub-group and appertaining to the call-seeker next in order of the next sub-group is made currentless, whereby the lifting electromagnet of this call-seeker is connected in circuit and the seeker lifted and 50 placed ready for receiving a further call in the sub-group in which the call took place. The lifted call-seeker releases the test line of the sub-group to which it was previously set, whereupon the call-seeker of the next 55 lower sub-group is lifted. Thus the call- 60

seekers move up in succession until a reserve seeker is lifted from the initial position to the first sub-group. If, for example, relay B¹ of the call-seeker AS¹ set to the fifth sub-group be energized, the ground connection of the switch spring s² will become interrupted at contact b^1 . Relay A³ of the call-seeker AS³ which becomes currentless closes its rest contact owing to its armature falling and connects to battery G the lifting 70 electromagnet H³ by way of the main battery feeder 100, conductor 36, coil of electromagnet H³, conductor 37, rest contact of relay A³, conductor 38, contact b^2 of relay B³, conductor 39, common circuit-breaker conductor 101 and circuit breaker U. Call-seeker AS³ is lifted until its spring s¹ contacts with contact k^5 of switch SS³. Relay A³ is then energized by way of spring s¹, contact k^5 , line 16 and ground and disconnects the lifting electromagnet H³. When 80 spring s² of this seeker AS³ passes from contact k^{14} to contact k^{15} the test line 15 becomes grounded and the group obtained by seeker AS³ is thus closed to other call-seekers, whereas the ground is disconnected from test line 14 so that the seeker (not shown) set to the third sub-group can move forward to the fourth sub-group owing to the interpolation of its lifting electromagnet. The 85 described operation is repeated until the first reserve seeker AS² is lifted to the first sub-group. Test line 11 grounded by way of spring s² and contact 11 of switch SS² is then connected by way of conductor 9 at the first call-seeker, conductor 8 and the head contacts h^1 , h^2 , h^3 of the call-seekers AS¹, AS², AS³ with the relay A⁴ of the call-seeker AS⁴ which is energized in this manner. 90

The subscribers' stations are connected with the central station by way of double lines (Fig. 1) which are combined in the central station to groups of 100, for example. Each line of a group leads in multiple 100 to the banks of contacts of the connector and call-seeker of its group and is connected by way of contacts t^3 , t^4 of a cut-off relay TR to a call relay R. Each subscriber's line possesses its own call relay and its own cut-off 105 relay. 110

The calls in the individual sub-groups are received independently one of another and may occur simultaneously in the various sub-groups. In order to bring about that when only one call is present in one sub-group, only one call-seeker is moved along the contacts of this sub-group, and, when two or more calls are present simultaneously in the same sub-group that two or more call-seekers are started in succession and moved simultaneously along the contacts of this sub-group, each sub-group is provided with a starting relay E (Fig. 1) having two differential 115 120 125 130

coils e^1 , e^2 . Each cut-off relay TR of a subscriber's line is provided with a coil t^1 of relatively high resistance and a coil t^2 of relatively low resistance. The coil t^1 is permanently connected with a test line d leading to those test contacts in the connectors which belong to the subscriber's station. The coil t^2 is connected with the test line c leading to the test contacts of the call-seekers. Moreover, the test lines of the call-seekers are connected by way of contacts t^5 of the cut-off relays TR and by way of individual series resistances z with the coil e^1 of the common starting relay E of the sub-group in question, whereas the coil e^2 is connected with a series resistance q^5 common to the sub-group. When a call relay R operates both the coils of relay E are connected in circuit, the action of the current in coil e^1 exceeding that of the current in coil e^2 . If, for example, call relay R³⁸⁹ of subscriber T³⁸⁰ operates, it closes the contacts r^1 , r^2 . Then a current flows from the grounded battery G by way of feeder 100, conductor 40, and from here on the one hand by way of coil e^1 of relay E⁵, conductors 41, 42, individual series resistance z^{389} , conductor 43, contact t^5 of relay TR³⁸⁹, conductor 44, coil t^2 of relay TR³⁸⁹, conductor 45, contact r^1 of relay R³⁸⁹, and on the other hand by way of coil e^2 of relay E⁵, common series resistance q^5 , conductors 46, 47, contact r^2 of relay R³⁸⁹, thence together with the current supplied by way of coil e^1 by way of conductor 48, contact t^6 , ground and back to the battery. The coils e^1 , e^2 are alike, whereas resistance q^5 which is in series with winding e^2 is greater than the individual resistance z^{389} in series with coil e^1 . Consequently the current in coil e^1 exceeds that in coil e^2 and relay E⁵ is energized. Relay TR³⁸⁹ which only operates when there is a materially stronger current in coil t^2 cannot, however, attract its armature. Owing to the contact e^3 at relay E⁵ being closed relay B¹ of the call-seeker AS¹ set to the fifth sub-group, to which the calling subscriber belongs, is energized. Referring to Fig. 2, current flows from battery G by way of feeder 100, conductors 26, 49, coil of relay B¹, rest contact b^3 , conductor 50, switch spring s^3 , contact k^{25} , conductor 25 (Fig. 1), contact e^3 , conductors 51, 46, 47, contact r^2 of relay R³⁸⁹, conductor 48, contact t^6 to ground. By attracting its armature the energized relay B¹ brings about the following changes in connection: By opening contact b^3 and closing contact b^4 the coil of relay B¹ is disconnected from switch spring s^3 and connected in a local holding circuit by way of contact b^4 , conductor 52, contact h^4 , ground, and kept energized during the connection; by opening contact b^1 ground is disconnected from spring s^2 , whereby the next call-seeker is

caused to move forward toward this sub-group, and by opening contact b^2 and closing contact b^5 lifting electromagnet H¹ of the call-seeker is disconnected and turning electromagnet D¹ connected in the following local holding circuit: battery G, feeder 100, conductor 53, contact n^1 of a relay N¹, conductor 54, contact p^3 of relay P¹, conductor 55, contact p^3 of relay P², conductor 56, winding of turning electromagnet D¹, conductor 56', contact b^5 , conductor 57, conductor 101, circuit-breaker U, ground. After the first rotary step of call-seeker AS¹ the test levers o^1 , o^4 contact with the first contacts of the test lines of the ninth and tenth rows of contacts, and then there are two shunts to the coil e^1 of relay E⁵, to wit, current flowing by way of the individual resistance z^{389} branches at conductor 41 and flows on the one hand by way of resistance z^{381} , contact t^5 of relay TR³⁸¹, line c^{381} , switch spring o^1 , conductor 58, coil of relay P¹, series resistance w^1 , conductor 59, contact p^4 of relay P², conductor 60, contact n^2 of relay N¹, conductor 53, feeder 100, and on the other hand by way of resistance z^{391} , contact t^5 of relay TR³⁹¹, line c^{391} , switch spring o^4 , conductor 61, coil of relay P², series resistance w^2 , conductor 62, contact p^4 of relay P¹, conductor 60, contact n^2 of relay N¹, conductor 53, feeder 100 to battery G. The individual resistances z^{381} and z^{391} and the resistances w^1 , w^2 of relays P¹, P² are so proportioned relatively to the coil e^1 that the current in this coil e^1 is now equivalent to that in coil e^2 , whereby the armature of relay E is caused to fall. When the contacts o^1 , o^4 are turned farther along the test contacts of the sub-group, instead of the resistances z^{381} , z^{391} the individual resistances of the subscribers' lines 382 and 292, and so on, are connected in series. Relay B³ of the call-seeker AS² raised in the meantime from the rear sub-group to this one on account of the current of relay A³ being switched off onto contact b^1 of relay B¹ would thus obtain no current and not connect in series its turning electromagnet.

At the short transition moment of the switch-lever from one test contact to the other two individual resistances are each time connected in parallel. The short time of transition, however, does not suffice for influencing relay E. In addition, the currents in the coils of relays P¹, P² serving for testing the lines and in the relay TR³⁸⁹ are not sufficient to operate the relays. Only when switch-lever o^1 has arrived at contact 89 does a stronger current flow from battery G by way of feeder 100, conductor 53, contact n^2 of relay N¹, conductor 60, contact p^4 of relay P², conductor 59, resistance w^1 , relay P¹, conductor 58, switch-lever o^1 , line c^{389} , coil t^2 , conductor 45, contact r^1 ,

conductor 48, contact t^6 to ground. Relays TR^{389} and P^1 are consequently energized. When relay TR^{389} attracts its armature it makes the following changes in connections: 5 to wit, relay R^{389} is disconnected from subscriber's line a^{389}, b^{389} at the contacts t^3, t^4 , resistance z^{389} is disconnected from test line c^{389} at contact t^5 , and ground from conductor 48 at contact t^6 . At the same time it 10 connects test line c^{389} with the relatively high resistance coil t^1 and with the test wire d^{389} at contact t^1 leading to the connector. The disconnected relay R^{389} likewise releases its armature and the circuits of the coils 15 e^1, e^2 of relay E and also of coil t^2 of relay TR^{389} are finally disconnected. Test relay P^1 disconnects the turning electro-magnet D^1 at contact p^3 , test relay P^2 at contact p^4 , and effects the connection of the lines $a^{172}, 20 b^{172}, c^{172}$, leading to the first selector by way of the contacts p^1, p^2, p^5 , respectively, with the switch-levers o^2, o^3 and battery G , while resistance w^1 becomes short-circuited at contact p^6 . The subscriber's line a^{389}, b^{389} is 25 now connected by way of switch-lever o^2 , contact p^1 , line a^{31} , line a^{31} (Fig. 3), and by way of switch-lever o^3 , contact p^2 , line b^{172} , line b^{31} (Fig. 3), to the line relays A^{31}, B^{31}, X^{31} of a first selector GW^{31} (Fig. 3). By 30 short-circuiting resistance w^1 , a fall of potential is brought about at the test lines c^{389} and d^{389} thereby preventing a second call-seeker or a connector being connected to these lines. If, on the contrary, two calls 35 are present simultaneously in one sub-group, the current in coil e^1 of the starting relay exceeds the current in coil e^2 even when the test relays of the call-seeker moving over the contacts of this sub-group are connected 40 in parallel with coil e^1 by way of the individual resistances of the test lines which are contacted at any time while the seeker rotates. For example, if the subscriber T^{389} or 45 during the rotation of the switch-levers of call-seeker AS^1 , relay R^{389} (Fig. 1) also closes its contacts r^1, r^2 . While only the series resistance q^5 is interpolated in the circuit of coil e^2 of relay E^5 , the series resistances z^{389} and z^{388} are connected in parallel 50 in the circuit of coil e^1 . Consequently, in spite of the shunts by way of the individual resistances to the contacts contacted at any time by the switch-levers o^1, o^4 of call-seeker 55 AS^1 , and by way of the test relays P^1, P^2 connected with the switch arms o^1, o^4 , the current in coil e^1 will be stronger than that in coil e^2 . Thus relay E^5 will remain energized so that relay B^5 of the call-seeker AS^5 60 now lifted to this sub-group also receives current and its turning electromagnet is at once connected in circuit, whereas at the contact b^1 of relay B^5 , owing to the ground being disconnected from the test line of the

sub-group, a third call-seeker is caused to 65 move up at once to this sub-group. Only after the first rotary step of call-seeker AS^8 and after the interpolation of its test relay in parallel with coil e^1 by way of two additional individual resistances is the current withdrawn 70 from winding e^1 to such an extent that the armature of relay E^5 can fall. If, for example, the coils e^1 and e^2 are of equal resistance and like numbers of turns, and if the resistance q^5 is twice as large as an individual resistance together with coil t^2 of a relay TR , and if an individual resistance together with the winding of a test relay P and the resistance in series with this coil is twice as great as the resistance of coil e^1 , 75 the difference of the current in coils e^1, e^2 when calling may be designated J . When the switch-lever of a call-seeker slides over the test contacts the difference of the currents in these windings is zero. If, on the contrary, there are two calls, the difference of the currents in the coils e^1, e^2 during the 80 parallel connection of the two test relays to coil e^1 is again equal to J and relay E remains energized until, after connection in 85 parallel with coil e^1 of the test relays of the call-seeker which started second, the current in this coil e^1 is diminished to such an extent that the armature of the relay can fall.

As follows from the above, for reaching 90 the contacts of a calling line after the operation of a call-relay the call-seeker has only to make the rotary steps in the sub-group, whereas when two calls are present simultaneously in one sub-group, for reaching the 95 second calling line the second call-seeker has to make in addition the lifting step from the lower sub-group toward this sub-group. When the call-seeker is raised from sub-group to sub-group by one step, only the 100 time of a lifting step is added to the rotary steps; on the contrary, if the call-seeker is lifted from contact row to contact row two 105 lifting steps are added.

During the connection of the calling line 110 by way of the contacts of the test relay P^1 with the first selector GW^{31} (Fig. 3) the operative electromagnet S^{31} of the side controlling switch ST^{31} of this selector is at once energized in the following circuit: battery G (Fig. 2), feeder 100, conductor 53, contact n^2 of relay N^1 , conductor 60, contact p^5 , conductor c^{172} , conductor c^{31} (Fig. 3), electromagnet S^{31} , lever s^{32} of the side switch ST^{31} in its first position, conductors 63, 101, 115 circuit-breaker U , ground. After the circuit has been closed at the circuit-breaker U and opened again the controlling switch ST^{31} moves from the first into the second position. If the line relays A^{31}, B^{31} (Fig. 3) 120 of selector GW^{31} connected in the meantime with lines a^{389}, b^{389} have not been energized for any reason, call-seeker AS^1 is at once

released, a current flowing from battery G (Fig. 2) by way of feeder 100, conductor 64, electromagnet M¹ serving for releasing the seeker, conductor 65, releasing relay N¹, 5 contact n³, line m¹⁷², conductor m³¹ (Fig. 3), rest contact b¹ of relay B³¹, conductor 66, contact p¹ of test relay P³¹, conductor 67, lever S³¹ in its second position, ground and back to the battery. The energized relay 10 N¹ holds the releasing circuit by way of contact n⁴, conductor 68 and contact h⁴ closed until the call-seeker returns into its initial position and opens contact h². The test relays P¹, P² and the lifting and turning elec- 15 tromagnets H¹ and D¹ are kept cut-out, while the call-seeker returns, by the contacts n¹, n² which are interrupted when relay N¹ operates. After contact h⁴ has been opened by the falling switch shaft of the 20 seeker, the current in electromagnet M¹ and in relays B¹ and N¹ is interrupted, whereas the connection of contact h⁰ with test line 10 is done away with by opening contact h¹; call-seeker AS¹ then remains in the initial 25 position as first reserved seeker. Simulta- neously with the described closure of the releasing circuit for the call-seeker, the re- leasing electro-magnets N³¹, M³¹ of side switch ST³¹ and of selector GW³¹ are con- 30 nected in circuit by way of conductor 69, so that the side switch also returns into its normal position. The object of this testing of the telephone branches of the calling line is to return the call-seeker into its normal 35 position when the calling subscriber, without selecting, replaces his receiver on the hook-switch.

For connecting into circuit the releasing circuit by way of the electromagnets M and 40 N there is provided at every call-seeker a contact i which is closed every time the call- seeker, when rotating, is not stopped at any of the subscribers' contacts of a sub-group and has been rotated beyond the row of the 45 same. This might be the case when the test line of the calling subscriber at this call- seeker is faulty or when the subscriber breaks off the call while the call-seeker is rotating. The same case can also occur, if, 50 when one of the test levers passes over an engaged line, on account of the disconnected individual resistance of the same insufficient current is withdrawn at this moment from coil e¹ of relay E, so that the call-seeker 55 which is set in the meantime to the same sub-group likewise connects its turning mag- net in circuit. The last mentioned call- seeker which then finds no calling line closes contact i after running through the row of 60 contacts so that it is released and thrown down.

In the modified system according to Figs. 5 and 6 the call-seekers of the groups of subscribers are not connected permanently

with "first" selectors, but are connected 65 with these by way of a system of "second" call-seekers. In this manner the same "first" selectors are made accessible for several groups of subscribers. Since the number of call-seekers per group of subscribers 70 must be greater by a certain amount, on account of the arrangement of sub-groups, than the number of the connections pro- ceeding simultaneously from one group of subscribers, as a seeker must always remain 75 set in front of each sub-group the number of the "first" selectors must be correspond- ingly greater when the call-seekers of the group of subscribers are connected directly 80 with the "first" selectors. When employ- 85 ing automatic switches for connecting the call-seekers of the groups of subscribers with idle "first" selectors, on the contrary, the number of the required "first" selec- tors may be considerably less than that of the call-seekers. For, on the one hand, as found in practice, the percentage of simulta- neously-speaking subscribers out of a 90 large number is less than, for example, in a group of only 100 subscribers, so that for this reason a less number of first selectors is required when they are accessible to several 95 groups of subscribers, but, on the other hand, the number of the same does not re- quire to be increased corresponding to the greater need for call-seekers, since each of the idle seekers does not engage a first selec- 100 tor as in the case of a fixed connection of seekers and selectors.

The arrangement according to Figs. 5 and 6 is to be thought of as inserted be- 105 tween the arrangement according to Figs. 2 and 3. The lines running out at the right of Fig. 2 now lead to Figs. 5 and 6, whereas the lines running out of Fig. 6 lead first 110 to the similarly designated lines of Fig. 3. In addition, unimportant changes in the 115 connection according to Fig. 2 are necessary and indicated therein in dotted lines. A calling line is also now connected without any delay with a first selector by way of the contacts of the call-seeker of a group 120 of subscribers and by way of the contacts of the additional automatic switching de- vices: the set of contacts of these switching 125 devices are also divided into sub-groups and here also one switching device or apparatus is set by preparing steps to each sub-group. The switching devices thus likewise form call-seekers and are designated "second" 130 call-seekers hereinafter. When a call is present, a "second" call-seeker is started at once simultaneously with the "first" call- seeker. As every "second" call-seeker can 135 reach 100 lines of the "first" call-seekers, whereas in each group of subscribers about 140 18 call-seekers are required, the "second" call-seekers and the "first" selectors con- 145 nected with these can serve for, say, 7

groups of subscribers. But in order to make the same "first" selectors accessible to a still larger number of groups of subscribers, the lines of the call-seekers of the groups 5 of subscribers are led to different groups of the second call-seekers and for the purpose of mixing them better are connected to different sub-groups in the same group. Thus in Fig. 6 the lines a^{172} , b^{172} of call-seeker AS¹ and the lines a^{183} , b^{183} of call-seeker AS² are connected to the sets of contacts of the "second" call-seekers AS¹¹, AS¹², and so on, while the lines a^{294} , b^{294} of call-seeker AS³ and the lines a^{285} , b^{285} of call-seeker 10 AS⁴ of the same group of subscribers are connected to the sets of contacts of the second call-seeker AS²¹, and so on, of another group, to wit the lines a^{172} , b^{172} are connected to the fourth sub-group of the call- 15 seekers AS¹¹, AS¹², and so on, while the lines a^{183} , b^{183} of the call-seeker AS² are connected to the fifth sub-group of the same selector. In like manner as the call-seekers according to Fig. 2, the "second" call- 20 seekers are also provided with switches SS which are driven only in the one direction and examine the sub-groups, so that on each sub-group only one free call-seeker is ready to be set on the contacts of a first call- 25 seeker occupied at a group of subscribers for a call. In similar manner, here also the test line of the sub-group is engaged by the switch spring s^{12} and the test line of the advance or higher sub-group is tested by 30 means of the switch spring s^{11} and the relay A¹¹, whereas the calls at the sub-group are received by means of relay B¹¹ by way of the switch spring s^{13} . The second call- 35 seekers are also provided with test levers o^{11} , o^{14} and test relays p^{11} , p^{12} in order simultaneously to test two horizontal rows of contacts of one sub-group.

When a relay B of a call-seeker for the subscribers' lines operates a starting relay 40 in the corresponding sub-groups of the "second" call-seekers is switched into circuit, whereby a "second" call-seeker is started simultaneously with the "first" call-seeker. As soon as relay B¹ of call-seeker AS¹ has 45 been energized when subscriber T³⁸⁹ is being called, as described above, it closes the contacts b^6 , b^7 provided for the "second" call-seekers, when a current flows from battery G on the one hand by way of feeder 100 (Fig. 5), conductor 105, coil e^1 of relay E¹⁵, conductor 106, resistance w^{172} , conductor 107, contact t^3 of relay TR¹⁷², conductor 108, coil t^2 , conductor 109, contact t^5 of 50 relay TH¹⁷², conductor 110 (Fig. 2), contact b^6 of relay B¹, conductor 52, head contact h^4 to ground, and, on the other hand, by way of feeder 100 (Fig. 5), conductor 105, coil e^2 of relay E¹⁵, series resistance g^{15} , conductors 111, 112, contact t^6 of relay TH¹⁷², con-

tact t^7 of relay R¹⁷², conductor 113 (Fig. 2), contact b^7 of relay B¹ to ground. As resistance g^{15} is greater than resistance w^{172} the current in coil e^1 exceeds that in coil e^2 , and by attracting its armature relay E¹⁵ closes contact e^3 , whereby relay B¹¹ of the "second" call-seeker AS¹¹ set to the fourth sub-group is energized in the following circuit:—battery G, feeder 100 (Fig. 6), conductor 114, relay B¹¹, rest contact b^3 , conductor 115, switch-lever s^{113} , conductor 116 (Fig. 5), contact e^3 of relay E¹⁵, conductors 117, 111, 112, contact t^6 of relay TH¹⁷², conductor 113 (Fig. 2), contact b^7 of relay B¹, ground. The energized relay B¹¹ switches its own coil for the duration of 80 the connection into a holding circuit by way of contact b^4 , conductor 118, head contact h^{12} to ground and the turning electromagnet D¹¹ of the seeker by way of feeder 100, conductor 119, contact n^1 of the releasing relay N¹¹, conductor 120, contact p^3 of the test relay P¹¹, conductor 121, contact p^3 of the test relay P¹², conductor 122, electromagnet D¹¹, contact b^5 of relay B¹¹, conductors 123, 101 and circuit-breaker U to the 90 battery G, and causes the switch-levers o^{11} to o^{16} to rotate at the contacts of the fourth sub-group, whereas by opening contact b^1 relay A¹² of call-seeker AS¹² is made currentless, whereby the lifting electromagnet 95 H¹² of seeker AS¹² is cut into circuit and this seeker is lifted to the fourth sub-group. As soon as switch-lever o^{14} of call-seeker AS¹¹ contacts with test line c^{172} a stronger current flows from battery G by way of 100 feeder 100 (Fig. 6), conductor 119, contact n^2 of relay N¹¹, conductor 124, contact p^4 of test relay P¹¹, conductor 125, resistance w_{c12} , test relay P¹², conductor 126, switch-lever o^{14} , conductor c^{172} (Fig. 5), coil t^2 105 of relay TR¹⁷², conductor 109, contact t^5 of relay TH¹⁷², conductor 110 (Fig. 2), contact b^6 of relay B¹, conductor 52, contact h^2 to ground, whereby relays TR¹⁷² and P¹² are 110 energized. By attracting its armature relay TR¹⁷² interrupts at the contacts t^3 , t^7 the circuit of the coils e^1 and e^2 of relay E¹⁵, interpolates by way of contact t^4 and conductor 127 its relatively high resistance coil t^1 in the circuit of the test relay P¹², and at 115 contact t^8 interpolates the auxiliary cut-out relay TH¹⁷² in the following circuit: battery G, feeder 100 (Fig. 5) conductor 128, relay TH¹⁷², conductor 129, contact t^9 , conductor 127, 110 (Fig. 2), contact b^6 of relay 120 B¹, conductor 52, contact h^2 , ground. By breaking contact p^5 relay TH¹⁷² thus energized, cuts out coil t^2 of relay TR¹⁷² from test line c^{172} and maintains the circuit of its own coil by way of contact t^9 . By attracting its armature the energized relay P¹² disconnects the turning electromagnet 125 D¹¹ at contact p^3 , cuts out test relay P¹¹ at

contact p^4 , and effects the connection of the lines a^{31} , b^{31} , c^{31} , leading to the first selector GW^{31} by way of the contacts p^1 , p^2 , p^5 , respectively, with the switch levers o^{15} , o^{16} and 5 battery G, whereas resistance w^{12} is short-circuited at contact p^6 . Call-seeker AS^{11} now remains on lines a^{172} , b^{172} of call-seeker AS^1 independently as to whether the latter is still moving or has already arrived at the 10 contacts of the calling line. Electromagnet S^{31} of the first selector GW^{31} is connected to the battery G in the following circuit: feeder 100 (Fig. 6), conductor 119, contact n^2 of relay N^{11} , conductor 124, contact p^5 of 15 relay 12, conductor c^{31} (Fig. 3), electromagnet S^{31} , lever 32 of the side switch ST^{31} in its first position, conductor 63, feeder 100, circuit-breaker U, battery G, and moves controlling switch ST^{31} from the first into the 20 second position. If, in the meantime, the relays A^{31} , B^{31} of the selector connected with lines a^{172} , b^{172} are not energized, call seeker AS^{11} is at once released, current flowing from battery G by way of feeder 100 (Fig. 25 6), conductor 130, releasing electromagnet M^{11} , releasing relay N^{11} , contacts n^3 , m^{31} , m^{31} (Fig. 3), rest contact b^1 of relay B^{31} , conductor 66, contact p^1 of test relay P^{31} , conductor 67, second position of lever S^{31} to 30 ground and back to battery. In order that relays A^{31} , B^{31} can be energized when call-seeker AS^1 is still rotating and the connection with the calling line is not yet made, lines a^{172} , b^{172} (Fig. 2) are connected by way 35 of rest contacts p^7 , p^8 of relays P^1 and P^2 and a contact n^8 at relay N^1 . But if, after call-seeker AS^1 has reached the calling line and lines a^{172} , b^{172} have been connected by 40 way of contacts p^1 , p^2 of relay P^1 and the switch-levers o^2 , o^3 with the lines a^{389} , b^{389} , relays A^{31} , B^{31} of selector GW^{31} are not energized, the above described interpolation of releasing electromagnet M^{11} and releasing relay N^{11} of the second call-seeker 45 AS^{11} takes place. By interrupting its contact n^1 energized relay N^{11} then renders currentless relay TR^{172} , whose armature falls and closes contact t^{10} whereby the following releasing circuit of call-seeker 50 AS^1 is closed: grounded battery G, feeder 100 (Fig. 2), conductor 64, electromagnet M^1 , conductor 65, relay N^1 , contact n^3 , contact m^{172} (Fig. 2), contact t^{11} of relay TH^{172} , contact t^{10} of relay TR^{172} , conductors 55 127, 110 (Fig. 2) contacts b^6 of relay B^1 , conductor 52, contact h^4 , ground, and both call-seekers are brought into the rest position, while relay TH^{172} likewise becomes currentless after contact h^2 at call-seeker 60 AS^1 is broken. In like manner call-seeker AS^{11} would be released if when rotating it found no call-seeker which has been started for receiving a call at a subscriber's line and closes contact i^{11} . If, on the contrary, call-

seeker AS^1 when rotating found no calling line and closed contact i^4 , when relay N^1 is being energized the connection of the lines a^{172} , b^{172} at contact n^5 is opened and relays A^{31} , B^{31} are rendered currentless.

65

In the modified system according to Fig. 7 the switching devices for connecting the call-seekers with idle "first" selectors are formed as pre-selectors which are moved at the same time as the call-seekers are started and are stopped at the contacts of the lines leading to an idle "first" selector, it being indifferent whether the call-seeker is still moving or has already stopped at a calling line. The pre-selectors according to Fig. 7 are to be thought of as arranged between Figs. 2 and 3, the lines proceeding from Fig. 2 leading to Fig. 7, whereas the lines leading to Fig. 3 proceed from Fig. 7. In addition, the unimportant changes indicated by dotted lines in Figs. 2 and 3 must be taken into consideration. The pre-selectors connected to the call-seekers of one and the same groups of subscribers select at various groups of "first" selectors, whereby the latter are accessible to a large number of subscribers' lines. The lines a^{172} , b^{172} ; a^{182} , b^{182} ; a^{294} , b^{294} ; a^{285} , b^{285} proceeding from Fig. 2 lead in Fig. 7 correspondingly to the pre-selectors VW^1 , VW^2 , VW^3 , VW^4 , respectively, each of which tests the lines of 10 "first" selectors; 90 pre-selectors VW^1 , VW^2 connect with a group of first selectors, pre-selectors VW^3 , VW^4 with another group of the same. The lines of the "first" selectors are, moreover, displaced relatively to one another at the contacts of the pre-selectors, as shown in Fig. 7, from pre-selector to pre-selector, whereby a better mixing and consequently more uniform utilization of the first selectors is obtained. When relay B^1 of call-seeker AS^1 is operated relay B^{21} of the selector is simultaneously energized in the following circuit: grounded battery G, feeder 100 (Fig. 7), conductor 131, rest contact i^{21} of the pre-selector switch shaft, conductor 132, relay B^{21} , conductor 113 (Fig. 2), contact b^7 of relay B^1 , ground. The energized relay B^{21} interpolates the turning electromagnet D^{21} of the pre-selector in a circuit leading from battery G, by way of rest contact i^{21} , conductor 132, contact b^2 , electromagnet D^{21} , conductors 133, 101, circuit-breaker U to ground. The switch-levers o^{21} , o^{22} , o^{23} are moved over the contacts of the lines leading to the first selectors. After the first rotary step of pre-selector VW^1 line 131 is switched over, without interrupting the current, from conductor 132 to conductor 134 by closing contact i^{22} and opening i^{21} . The currents in the coils of relay B^{21} and turning electromagnet D^{21} are maintained by way of conductor 131, contact i^{22} , conductor 134, contact p^3 of the test relay P^{21} , con- 105 110 115 120 125

ductor 135 and contact b^2 of relay B^{21} . As soon as switch-lever o^{21} has reached the test line n^{31} of a free first selector, the following circuit is closed: grounded battery G, feeder 100, conductor 136, contact b^3 of relay B^{21} , resistance w^{21} , relay P^{21} , switch-lever o^{21} , test line n^{31} (Figs. 7 and 3), relay V^{31} , first position of the switch-lever s^{31} of the controlling switch ST^{31} , ground. The relays P^{21} and 10 V^{31} are operated. The energized relay P^{21} disconnects at contact p^3 the relay B^{21} and turning electromagnet D^{21} , connects by way of contacts p^1, p^2 the lines a^{12}, b^{12} with the lines a^{31}, b^{31} , and directly connects at contact 15 p^5 the battery to the coil of relay p^{21} by way of feeder 100, conductors 131, 134 and contact p^5 . The energized relay V^{31} interposes electromagnet S^{31} in the following circuit: battery G, feeder 100, conductor 137, 20 contact v^1 of relay V^{31} , conductors 138, c^{31} , electromagnet S^{31} , switch-lever 32 in the first position, conductor 63, circuit-breaker U, ground. If, after the controlling switch ST^{31} has been brought into the second position, the relays A^{31}, B^{31} have not been energized in the meantime, the releasing electromagnet N^{31} is cut in and test line n^{31} is disconnected at switch-lever s^{31} . The relay P^{21} which has become currentless drops its armature and closes again the circuit of turning electromagnet D^{21} at contact p^3 , and connects the releasing magnet M^1 of the call-seeker AS in the following circuit: battery G, feeder 100 (Fig. 2), conductor 64, electromagnet M^1 , conductor 65, relay N^1 , contact n^3 , conductor m^{12} (Fig. 7), contact i^{23} , conductor 139, contact p^4 of relay P^{21} , conductor 140, contact b^1 of relay B^{21} , conductor 110 (Fig. 2), contact b^6 of relay B^1 , conductor 52, contact h^4 , ground, whereby the call-seeker is thrown back, while the pre-selector rotates further until the current for the turning electromagnet of the switch shaft is cut off by opening contact i^{22} . The 40 numbered switch at the subscriber's station comprises a finger dial which when wound up grounds both branches a, b of the line and when returning makes interruptions in the a -branch, whereas the b -branch remains continuously grounded in the meantime. When the numbered dial returns into its rest or normal position the ground is disconnected from both the branches and the latter are connected in series by way of the microphone at the station.

At the "first" selectors GW, e. g. GW^{31} in Fig. 3, are arranged three line relays A, B, X, of which relay X has differential coils which neutralize one another when both coils are connected in series by way of a subscriber's line. When the line branch is grounded at the number switch of the stations the armature of relay X is attracted and closes a local holding circuit for the coil

of relay B. In like manner, at the connectors LW, e. g. LW^{41} in Fig. 4, three line relays A, B, X are provided for the calling subscriber's line and in addition a supervisory relay Y for the called subscriber's line. Backward testing of the branches a, b has not been provided at the connector, and the controlling switch of the same makes no preparing step when the connector is engaged by a selector.

Making a complete telephonic connection 75 between two subscribers will now be described with reference to Figs. 1, 2, 3 and 4, the lines proceeding from Fig. 2 being thought of as leading directly to Fig. 3. The telephonic connection of two subscribers 80 in the modified system according to Figs. 5, 6 or 7 will then be readily understood having regard to what has been explained above.

The system operates as follows: Subscriber 85 389 of the fifth sub-group in the fourth group of subscribers wishes to be telephonically connected with subscriber 456. He takes up his telephone R^e from the hook-switch H^a and rotates his dial F^i by inserting his finger in the fourth hole. After removing the telephone R^e from the hook-switch H^a a current flows from battery G by way of feeder 100, conductor 141, coil 1 of relay R^{389} , conductor 142, contact t^3 of relay TR^{389} , line branch a^{389} , hook-switch H^a , primary induction coil p , microphone M^i and the choking coil D^i in parallel with the latter, line branch b^{389} , contact t^4 of relay TR^{389} , conductor 143, coil 2 of relay R^{389} , to ground and back to the battery. The energized relay R^{389} , whose coil 1 remains energized while numbered dial F^i is being wound up and the line branch is being grounded by way of spring f^i , closes the contacts r^1, r^2 , whereby current traverses the coils e^1, e^2 of 90 relay E^i . The stronger current in coil e^1 closes contact e^3 and relay B^1 of call-seeker S^1 is hereby energized. The latter cuts into circuit the turning electromagnet D^i at contact b^5 and simultaneously releases the test line 95 15 of the sub-group in question by opening contact b^1 , whereby another call-seeker is lifted toward this. The turning electromagnet D^i moves the switch-levers o^1 to o^6 of the call-seeker over contacts of the fifth 100 sub-group until the switch-lever o^1 has reached the test line c^{389} . The test relay p^1 and the coil t^2 of the cut-out relay TR^{389} are then energized by way of the test line. Relay TR^{389} disconnects relay R^{389} from the 105 line branches and interrupts the current in the coils e^1, e^2 of relay E^i , and also connects to the test line c^{389} the high resistance coil t^1 and the test line d^{389} of the connector of this group of subscribers connected with this coil. 110 When attracting its armature, relay P^i disconnects the turning electromagnet D^i and test relay P^2 , short circuits series resistance 115 120 125

w^1 , connects the line branch of the calling subscriber with the line branches of the first selector GW^{31} , and also closes the circuit of the selector electromagnet S^{31} connected to the circuit-breaker U . By short-circuiting resistance w^1 and disconnecting coil t^2 of relay TR^{389} at relay R^{389} a fall of potential is brought about at the test line c^{389} , d^{389} preventing the interpolation of another call-seeker or a connector in the line, while, owing to the interpolation of electromagnet S^{31} , controlling switch ST^{31} is moved from the first into the second position when the circuit is subsequently broken at the circuit-breaker U . Immediately after test relay P^1 has been energized the following circuit is closed: battery G , feeder 100 (Fig. 3), conductor 144, relay A^{31} , coil x^1 of relay X^{31} , conductor 145, switch-lever s^{35} of controlling switch ST^{31} , conductor a^{31} , conductor a^{172} (Fig. 2), contact p^1 of relay P^1 , switch-lever o^2 , branch a^{389} (Fig. 1), hook-switch H^a , contact p^s , microphone M^1 , branch b^{389} (Fig. 2), switch-lever o^3 , contact p^2 of relay P^1 , conductors b^{172} , b^{31} (Fig. 3), switch-lever s^{34} , coil x^2 of relay x^{31} , relay B^{31} , ground, and the relays A^{31} , B^{31} become energized.

When winding up the dial F^1 at the subscriber's station, by grounding the line branch current is withdrawn from coil x^2 so that coil x^1 traversed by current energizes relay X^{31} and contacts x^3 , x^4 are closed. By closing contact x^3 current in relay B^{31} is maintained from battery G by way of feeder 100, conductor 146, series resistance w^6 , contact x^3 , relay B^{31} and ground, and simultaneously a weak current flows in the reverse direction in the coil x^2 and line branch b^{389} preventing the armature of relay X^{31} falling even during impulses of current by way of the line branch a^{389} . In the second position of the controlling switch ST^{31} electromagnet S^{31} is energized again by way of switch-lever s^{32} , conductor 147, contact x^4 , ground. The energized relay B^{31} hereby keeps the releasing circuit of selector GW^{31} and call-seeker AS^{31} open. When the number switch returns branch line a^{389} is interrupted four times and relay A^{31} which begins currentless connects each time, owing to its armature falling, the lifting electromagnet H^{31} to battery G by way of feeder 100, conductor 148, switch-lever s^{33} , conductor 149, electromagnet H^{31} , rest contact of relay A^{31} , conductor 147, contact x^4 and ground. After the last interruption of the branch line a^{389} the ground is disconnected from the branch lines at the number switch at the station. Both branch lines are then connected in series again by way of the microphone, and relay X^{31} allows its armature to fall whereas relays A^{31} , B^{31} remain energized. Owing to the interruption of the current in the coil of the electromagnet

S^{31} at contact x^4 the controlling switch is moved into the third position. Electromagnet S^{31} is again energized by way of switch-lever s^{32} , conductor 66, contact p^1 of relay P^{31} , conductor 67, contact h^{31} , of the switch shaft and ground. The turning electromagnet is then connected to battery G by way of conductor 148, switch-lever 33, conductor 150, contact p^3 of test relay P^{31} , electromagnet D^{31} , conductor 101, circuit-breaker U and ground and rotates the switch-levers o^{31} , o^{32} , o^{33} over the contacts of the test and telephone lines of the connectors. As soon as switch-lever o^{31} has reached line c^{201} of the first free connector LW^{41} , test relay P^{31} is energized in the following circuit: battery G , feeder 100 (Fig. 4), conductor 202, rest contact h^{41} of the switch shaft, conductor 203, series resistance w^{201} , line c^{201} , switch-lever o^{31} , test relay P^{31} , resistance w^{31} , conductor 151, switch-lever 31 and ground. By opening its contacts p^1 and p^3 the energized relay P^{31} renders the electromagnets S^{31} , D^{31} currentless and short-circuits at contact p^2 the resistance w^{31} . A fall of potential then exists at the line c^{201} and prevents a second testing relay on this line being energized, while electromagnet S^{31} which has become currentless brings the controlling switch ST^{31} to the fourth position, in which the relays A^{31} , B^{31} , X^{31} of the selector GW^{31} are disconnected from the lines a^{31} , b^{31} , and the lines a^{31} , b^{31} connected with the branch lines a^{389} , b^{389} are connected by way of switch-lever s^{35} , conductor 152, switch-lever o^{32} or switch-lever s^{34} , conductor 153, switch-lever o^{33} , respectively, with the branch lines a^{201} , b^{201} and thus with the relays A^{41} , B^{41} , X^{41} of the connector LW^{41} . In spite of relay B^{31} having become currentless, the closure of the releasing circuit for the selector GW^{31} and the call-seeker AS^{31} cannot take place on account of the open contact p^1 at relay P^{31} . In like manner as previously the corresponding relays of selector GW^{31} , the relays A^{41} , B^{41} , X^{41} are now energized by way of the subscriber's branches, by closing contact x^4 relay X^{41} , which is energized corresponding to the tens of the required number when the numbered dial is wound up, interpolates electromagnet S^{41} in the following circuit: battery G , feeder 100, conductors 204, 205, contact x^4 , conductor 206, switch-lever s^{42} , series resistance w^8 , conductor 207, electromagnet S^{41} , ground. When the dial returns, at each interruption of the branch line a^{389} relay A^{41} connects the lifting electromagnet H^{41} in the circuit: Battery G , feeder 100, conductors 204, 205, contact x^4 , conductor 206, rest contact of relay A^{41} , conductor 208, electromagnet H^{41} switch-lever s^{41} , conductor 209, contact y^1 of the supervisory relay Y ground. After the first lift the rest

contact h^{41} of the switch shaft is opened, whereas the operative contact h^{42} is closed. The test line c^{201} remains connected to the battery, in spite of contact h^{41} being opened by way of conductor 210, contact b^2 of relay B^{41} , conductor 211, switch-lever s^{43} , conductor 212, contact y^2 of relay Y^{41} , conductor 213, feeder 100.

After the numbered dial has returned into its rest position electromagnet S^{41} becomes currentless owing to contact x^4 being opened and moves the controlling switch ST^{41} into the second position, electromagnet S^{41} being connected again to battery G in the following circuit: battery G, feeder 100, conductor 214, contact p^1 of test relay P^{41} , conductor 215, switch-lever s^{42} , resistance w^8 , electromagnet S^{41} , ground. After the numbered dial has been rotated again, corresponding to the units of the required number, relay X^{41} is energized again and when branch line a^{389} is interrupted during the return of the numbered dial, the turning electromagnet D^{41} of the connector is connected by relay A^{41} to the battery G by way of feeder 100, conductors 204, 205, contacts x^4 , conductor 206, rest contact of relay A^{41} , conductor 208, electromagnet D^{41} , switch-lever s^{41} in its second position, conductor 209, contact y^1 of relay Y to ground. As soon as relay X^{41} becomes currentless again after the sixth rotary step, owing to contact x^5 becoming closed the line d^{456} of the desired subscriber is tested, and when this is free the following circuit is closed: battery G, feeder 100, conductor 213, contact y^2 of relay Y , conductor 212, switch-lever s^{43} , conductor 211, contact b^2 of relay B^{41} , conductors 210, 203, contact x^5 of relay X^{41} , conductor 216, resistance w^{41} , relay P^{41} , switch-lever o^{41} , line d^{456} , coil t^1 of relay TR^{456} , ground. The relays P^{41} , TR^{456} are energized, and while the latter disconnects the call-relay R^{456} at the contacts t^3 , t^4 from the branch lines a^{456} , b^{456} and the individual series resistance z^{456} from the test line c^{453} leading to the sets of contacts of the call-seeker and connects together the test lines c^{456} , d^{456} by attracting its armature, relay p^{41} short-circuits the series resistance w^{41} at contact p^2 interpolates the choking coil D^{41} at contact p^3 and interrupts the current in electromagnet S^{41} at contact p^1 . By short-circuiting resistance w^{41} a fall of potential is produced at test lines d^{456} and c^{456} making the line appear engaged and preventing the excitation of the test relay of another connector or call-seeker testing on this, whereas owing to electromagnet S^{41} becoming currentless controlling switch ST^{41} is brought from the second into the third position. Electromagnet S^{41} is hereby again energized in the following circuit: battery G, feeder 100, conductor 213, con-

tact y^2 , conductors 212, 218, switch-levers 65 s^{42} , resistance w^8 , electromagnet S^{41} , ground.

If, on the contrary, the test relay P^{41} cannot be energized owing to the subscriber's line being engaged, the subscriber hears an "engaged" signal, since when the controlling switch remains in the second position the secondary coil of the common buzzer device SM (Fig. 4) emits current by way of condenser c^3 , contact z^{41} which is closed after the first rotary step of the connector, conductor 217, switch-lever s^{44} , condenser c^2 to the branch b^{201} and by way of this to the subscriber's station, which current produces a buzzing noise in the telephone of the station.

In the third position of the controlling switch the turning electromagnet D^{41} and the common buzzing device SM are disconnected and the lines a^{201} , b^{201} are connected by way of condenser c^1 , switch-lever s^{45} or by way of condenser c^2 , switch-lever s^{44} with the lines 220, 221, while a call relay L^{41} is interpolated in a local circuit proceeding from battery G, by way of feeder 100, conductor 222, a call distributing switch RV , conductor 223, call relay L^{41} , switch-lever s^{41} , conductor 209, contact y^1 of relay Y^{41} to ground. Whenever line 222 is connected with line 223 at the call distributor relay L^{41} is energized. By attracting its armature this relay causes a calling current to be sent to the station which is to be called from the calling source of current Q by way of conductor 224, contact l^1 of relay L^{41} , conductor 225, switch-lever o^{42} , line a^{456} , call-bell of station T^{456} , line b^{456} , switch-lever o^{43} , conductor 226, contact l^2 of relay L^{41} , conductor 227 and back to the calling source of current. During the pauses in calling, on the contrary, the conductors 225 and 226 are connected by way of contacts l^3 and l^4 , respectively, of relay L^{41} with the conductors 220, 221. As soon as the called subscriber takes his telephone from the hook-switch, the following feeding circuit to the microphone of the same is closed: source of current G, feeder 100, conductor 214, choking coil D^{41} , conductor 225, switch-lever o^{42} , line a^{456} , microphone of station T^{456} , line b^{456} , switch-lever o^{43} , conductor 226, contact l^4 of relay L^{41} , conductor 221, switch-lever s^{44} , conductor 228, relay Y^{41} , ground. The energized relay Y^{41} disconnects relay L^{41} at contact y^1 and affects the direct connection of line 211 with the battery G at contact y^3 , disconnects the battery from line 212 at contact y^2 and short-circuits the coil of electromagnet S^{41} at contact y^4 . Electromagnet S^{41} which has become currentless hereupon moves switch ST^{41} into the fourth position and the subscribers are finally telephonically connected. The telephonic circuit is as fol-

lows: station T^{389} , line a^{389} (Figs. 1 and 2), switch-lever o^2 , contact p^1 , line a^{172} , line a^{31} (Fig. 3), switch-lever s^{35} , conductor 152, switch-lever o^{32} , line a^{201} , condenser c^1 , 5 switch-lever s^{45} , conductor 220, contact l^3 , conductor 225, switch-lever o^{42} , line a^{456} , subscriber's station T^{456} , line b^{456} , switch-lever o^{43} , conductor 226, contact l^4 , conductor 221, switch-lever s^{44} , condenser c^2 , 10 line b^{201} , switch-lever o^{33} , conductor 153, switch-lever s^{34} , line b^{31} , line b^{172} (Fig. 2), contact p^2 , switch-lever o^3 , line b^{389} , line b^{389} (Fig. 1), and back to subscriber's station T^{389} . By replacing the telephone and making currentless the relay B^{41} and relay Y^{41} , the calling and called subscribers can each close the circuit of the releasing electromagnets M^{41} , N^{41} at contact b^1 and y^2 , respectively, and interrupt the current in line 15 c^{201} at contact b^2 and contact y^3 , respectively. If subscriber T^{456} replaces his telephone first, the electromagnets M^{41} , N^{41} are connected to battery G in the following circuit: battery G , feeder 100, conductor 213, 20 contact y^2 , conductor 212, switch-lever s^{43} , conductor 230, electromagnets M^{41} , N^{41} , conductor 231, contact h^{42} , ground; if, on the contrary, subscriber T^{389} replaces his telephone first, the releasing magnets are connected to battery G in the following circuit: battery G , feeder 100, conductor 213, 25 contact y^3 , conductor 211, contact b^1 , conductors 232, 230, electromagnets N^{41} , M^{41} , conductor 231, contact h^{42} , ground. Subscriber T^{389} can close the releasing circuit even when subscriber T^{456} has not announced himself, to wit by way of feeder 100, conductor 213, contact y^2 , conductor 212, switch-lever s^{43} in the first, second and 30 third positions, conductor 211, contact b^1 , conductors 232, 230, electromagnets N^{41} , M^{41} , conductor 231, contact h^{42} , ground. Owing to test line c^{201} becoming currentless after the interruption of the battery line at contact h^2 or y^3 , relay p^{31} allows its armature to fall. Contact p^1 is hereby closed and the circuit for the releasing electromagnets M^{31} , N^{31} of selector GW^{31} and electromagnets M^1 , N^1 of call-seekers AS^1 is simultaneously closed. Both selectors return into their rest or normal positions and call-seeker AS^1 is connected in its initial position to the reserve seekers of the subscriber's group. 35 For the purpose of fully disclosing my invention I have explained and described in detail some illustrative embodiments of the same which I consider necessary in order that it may be understood; but it is not to be understood that I limit myself to such illustrative embodiments in detail, as my invention comprehends a universal system, the specific forms of which admit of many

variations without departing from the spirit and scope of my invention. 65

I claim:

1. In an automatic telephone system the combination with a plurality of subscribers' lines and selecting and connecting devices for connecting a desired line with a calling line, of a call-seeking switching device, adapted to move in two kinds of switching steps to seek a calling line, banks of contacts in said switching device connected with subscribers' lines, said banks being divided in sub-groups, said switching devices moving in one kind of step independently of a call being present, relays and connections for moving a switching device in the other kind of step, when a call is received, to find the contacts of said bank connected with the calling line. 70

2. In an automatic telephone system comprising subscribers' stations, calling devices in each subscriber's station, an exchange, lines connecting said stations with the exchange, one calling device for each line in the exchange, call seeking devices adapted to move in two kinds of switching steps to seek a calling line, selectors and connectors for connecting in the exchange a calling station with the called station, said selectors and connectors being set by the calling devices in the stations, the combination of banks of contacts arranged in rows to which the lines of a group of subscribers are led in multiple connection, a call seeking switch provided with switch arms for each bank of contacts and means for setting said switch to a calling line, with means for setting one call seeking switch automatically to each part of the rows of contacts, which parts each form a sub-group in the group independently as to whether a call is present in the sub-group. 95

3. In an automatic telephone system, the combination of a plurality of subscribers' lines, switching means in each subscriber's station, an exchange, lines connecting said stations with the exchange, selectors and connectors for connecting in the exchange a calling station with the called station, of call-seeking devices to seek the calling line and to connect said line with an idle selector, combined with banks of contacts divided in sub-groups, connected with a group of subscribers' lines, relays for automatically setting call-seeking devices to each sub-group of contacts independently of a call being present, relays and switches preventing a second call-seeking device from stopping at a sub-group being already occupied by another seeking-device, relays for starting said call seeking-devices when a call is present in the sub-group to which they are set and for moving them to the contacts of a 100 110 115 120 125

calling line, a sufficient number of call seeking devices being provided for each group of subscribers' lines so that at least one idle reserve call seeking device is free for engagement, and releasing means to unlock the locking device of a sub-group when the call seeking device is started to take charge of a call, and relays for setting a reserve call seeking device to a sub-group as soon

as the call seeking device in reserve at this 10 sub-group has been started by a call.

In testimony whereof I have signed my name to this specification in the presence of two witnesses.

GEORG GRABE.
